OPERATING MECHANISM FOR FLUE DAMPERS

Wallace Bruce Mathews, Chicago, Ill., assignor to
Standard Oil Company, Chicago, Ill., a corporation of Indiana

Application February 19, 1932, Serial No. 594,048

1 Claim. (Cl. 196—116)

This invention relates to an operating mechanism for flue dampers located in underground flues connecting oil heaters to chimneys or stacks.

The object of my invention is to provide automatic means for opening such a damper in case of an emergency. The invention is particularly applicable for use in connection with pipe stills where oil is heated in tubes under high pressures; in case of tube failure my invention provides for a means whereby the fire is drawn through the flue and thence up through the stack or chimney so that as much of the heat as possible may be dissipated away from adjoining structures and so that operators may come close enough to the still to manipulate the necessary valves for shutting off the oil.

A further object is to provide an air-tight connection between the damper and the external operating means therefor. Other objects will be apparent from the following detailed description.

Briefly, I have provided a pivoted damper with a means for normally urging it into open position, said damper being, however, held in a predetermined position by an element which is designed to permit an automatic opening of the damper at elevated temperatures. In the particular embodiment shown, I provide a pivoted damper with an eccentrically mounted weight which normally urges it toward the open position and I provide a fusible link between the damper and the operating lever.

In the accompanying drawing wherein I have shown my preferred embodiment in detail and wherein similar parts are designated by like reference characters throughout the several views:

Figure 1 is an elevation partly in section showing the relation of my damper to an oil heater, flue and stack.

Figure 2 is an enlarged elevation or side view of the damper operating means.

Figure 3 is an end elevation of the damper operating means.

Figure 4 is a plan showing the cover of the flue opening and the socket or bearing in which the journal disk rotates, the superstructure being removed for simplicity.

Figure 5 is a vertical section through the journal socket or bearing.

Figure 6 shows a front and side view of one of the journal disks.

The invention will be described in connection with a pipe still 10 which is separated by baffle wall 11 into a combustion chamber 12 and a convection chamber 13. Roof, floor, and/or wall tubes 14 may be exposed to radiant heat in the

combustion chamber and a bank of tubes 15 may be suitably arranged in the convection chamber, the oil flowing through these tubes in any desired manner. The invention is not limited to any particular type of furnace, however, and is equally applicable to the so-called DeFlorez furnace wherein vertical tubes are arranged around a central burner. Likewise, the invention may be used with any other type or class of furnace where it is desired to employ an adjustable damper in an underground flue or where it is desired to provide an automatic means for opening such a damper in the event of abnormally high temperatures in the furnace.

The heater is connected by a flue 16 to a stack 15 or chimney 17. The flue is preferably underground, but I do not limit myself to this feature.

A damper 18 is pivoted in the flue on pin 19 so that when the damper is vertically disposed it closes the opening in the flue and when it is horizontally disposed it opens the flue to the fullest extent. A weight 20 is eccentrically mounted on the upper end of the damper so that it normally urges said damper in a clockwise direction about said pivot pin. A stop member 21 is arranged on the side or bottom of the flue which arrests the movement of weight 20 when the damper has assumed a horizontal position. It should be understood, of course, that other means, such as a tension spring, might be used to normally urge the damper in its open position.

A fusible link 22 is pivoted to one end of the top of damper 18 by pin *a* and at its other end to the bottom of lever 23 by pin *b*; this link may be designed to operate at temperatures of 500° F. or higher, and since per se fusible links are old in the art, I will not describe them in detail. Lever 23 extends through an opening 24 in the top of the flue casing and it also extends through and is secured in journal disk 25, this disk or ball being rotatable in a suitable bearing or socket as will be hereinafter described. The opening 24 is preferably defined by channel plates 26 on the sides thereof and plates 26a on the ends thereof, the end plates being slightly inclined as shown in Figure 2 to allow for movement of the operating lever. A rectangular plate 27 is secured to the top of the casing above the opening 24 by means of bolts 28 imbedded in the concrete. Plate 29 is preferably an integral part of plate 27, or it may be welded or secured thereto in any suitable manner. Plate 30 is held against plate 29 by bolts 31 which also hold the angle irons 32 that support the flared plates 33. Lever 23

is movable back and forth between plates 33 and 34 and is secured in any desired position by inserting pin 34 through one of the holes 35 in the flared plates and through a hole in lever 23, the movement of the lever in both directions being limited by bushings on bolts 36. These bolts and bushings serve to reinforce the flared plates and hold them in fixed position.

Referring to Figures 4, 5, and 6, it will be noted that the lower plate 29 is provided with a central opening. This opening is rectangular in horizontal section and in the transverse vertical section, but in the lengthwise vertical section the opening is circular with its maximum diameter in the plane of the top of the plate. Similarly, plate 30 is provided with a circular opening which registers with the opening in plate 29. Circular walls 37 in plate 29 and 38 in plate 30 act as bearings for the journal disk 25. This journal disk preferably consists of a pair of disks 40 provided with channels 41 for engaging the lever 23. Instead of using a pair of disks with co-operating channels, I may use a single disk with a diametric hole through which the lever may be inserted. A sphere or other journal member may be used instead of disks, the sockets or journals in plates 29 and 30 being designed accordingly.

The important feature is the use of a substantially air-tight journal, or bearing member so

that, under normal conditions, the products of combustion in the flue will not be unduly diluted and cooled by the infiltration of air.

While I have disclosed a weight for normally urging the damper to an open position, it should be understood that other means, such as a spring, may be employed. Instead of using a fusible link to releasably hold the damper in fixed position, I may employ a thermostatically operated damper opening means. Other expedients will be apparent to those skilled in the art and I do not limit myself to the above details except as defined by the following claim which should be construed as broadly as the prior art will permit.

15

I claim:

In combination, a furnace, a flue for carrying away the products of combustion of said furnace, a damper in said flue, means normally urging said flue damper into open position, and manually controllable means for opening and closing said damper independently of said first named means, said damper opening and closing means including a fusible link adapted to part under high flue temperatures, thereby to render said controllable opening and closing means ineffective and to render operative said means for urging said damper into open position.

WALLACE BRUCE MATHEWS.
